UNITED STATES PATENT OFFICE.

ROBERT R. HUGHES, JR., OF NYACK, NEW YORK, ASSIGNOR TO METROPOLITAN SEWING MACHINE COMPANY, OF NYACK, NEW YORK, A CORPORATION OF NEW YORK.

COLLARET-SEWING MACHINE.

1,052,058.

Specification of Letters Patent.

Patented Feb. 4, 1913.

Application filed July 27, 1912. Serial No. 711,777.

To all whom it may concern:

Be it known that I, ROBERT R. HUGHES, Jr., a citizen of the United States, residing at Nyack, in the county of Rockland and 5 State of New York, have invented certain new and useful Improvements in Collaret-Sewing Machines, of which the following is a specification.

This invention relates to sewing machines, 10 more particularly to an improved machine for stitching collarets or bindings to the necks of shirts or similar garments by means of which the width of the collaret or binding may be varied as occasion may require, 15 the object of the invention being to provide a machine of this kind in which the ends of the collaret are tapered by trimming a portion from each edge thereof in advance of and simultaneously with the stitching of 20 the collaret to the garment.

In the present machine the width of the collaret or binding strip is varied by automatically trimming off the surplus raw edges of the top and bottom of the strip 25 while the same is being fed by suitable feeding mechanism to the stitching mechanism, this being accomplished by the reciprocation of the trimming mechanism and the binding mechanism relatively to each other, 30 in the present instance by moving the binding attachment to and from the trimming mechanism in a peculiar manner whereby the result sought is obtained. Heretofore in order to make this tapered collaret finish it 35 was necessary to cut the collaret into narrow strips and then taper them on each end with scissors, each strip representing the length of a shirt neck. Then the strip was folded in the center and the neck of the 40 garment inserted between the edges of the folded strip and stitched on the ordinary twin needle sewing machine, making a stitch on the top and bottom, thus covering the raw edges of the collaret strip with the raw edge 45 of the body garment or neck between the two. This operation was somewhat difficult as well as expensive, and a uniform product could not be obtained.

The object, therefore, of the present improvement is to automatically taper the collaret strips during the stitching thereof to the garment.

In the present improvement the collaret or binding is simply cut to the proper

width and long lengths thereof are wound 55 on a roll of suitable size, which roll will be supported by some suitable means, as a reel, not shown, and provided with any suitable tension means. The end of the collaret is then passed through the binder provided for 60 that purpose, to the stitching mechanism, being fed thereto by some suitable feed mechanism, preferably of the differential type, so that the neck of the garment may be 65 fed into the collaret or binding as desired by regulating the movement of the differential feed. Between the binder guide and the stitching mechanism is located a suitable trimming mechanism and by the operation 70 automatically of the binder guide and the trimming mechanism relatively one to the other, in the present instance the binder guide, the collaret will be properly tapered in the manner about to be described. From 75 this it will be seen that the operation of stitching tapered collarets in the present improvement is greatly simplified, as the operator has simply to handle the shirt or garment so that the neck of the garment will be fed through the binder in the usual manner.

In a general way the present improvement consists of guiding mechanism for feeding the collaret or binding strip to the sewing mechanism and mechanism for trimming the 85 two edges of the strip so that the width of the collaret may be varied, together with means for shifting one of said mechanisms relatively to the other, in the present instance the guiding mechanism, and in such a way as to 90 make the taper of the collaret the same at each end thereof.

In the drawings accompanying and forming part of this specification, Figure 1 is a front view of this improved machine; Fig. 2 95 is a left hand end view of Fig. 1; Fig. 3 is a plan view of Fig. 1, with the overhanging arm in section taken on line 3—3, Fig. 1; Fig. 4 is a perspective view of the attachment removed from the machine; 100 Fig. 5 is a detail view of the actuating means for operating the trimmer knives; Fig. 6 is a detail view of the binder and the means for carrying the same; Fig. 7 is a detail view of a part of the binder mechanism shown in Fig. 6 and a part of the trimming mechanism; Fig. 8 is a view of the cam for shifting the binder; Fig. 9 is a view

of one form of throat plate which may be used with the present improvement; Fig. 10 is a view of one form of presser foot which may be used with the present improvement, this form of throat plate and presser foot being used when it is desired to turn the edges of the binding strip in as shown in Fig. 11.

Similar characters of reference indicate corresponding parts throughout the figures of the drawings.

In the present improvement the bed of the machine 1 has the usual goose-neck or overhanging arm 2, the overhanging portion 3 of which arm carries the usual presser foot bar 4 and needle bar 5 carrying twin needles.

This bar 5 is reciprocated in the usual manner by means of a link 6 connected with the needle lever 7 pivoted at 8 to the arm 2 and 15 operatively connected in the usual manner to the main driving shaft 10, which latter is provided with suitable mechanism to operate the stitching and feeding mechanism of that type which it may be desired to use.

When the collaret is to be stitched to the garment by a suitable covering stitch this may be obtained by providing two fingers 13, each carrying a thread that operates in front of the two needles 14, which coöperate 25 with a suitable looper 15 that connects its thread with the two needle threads to make the covering stitch on the bottom, while the cross finger threads produce the stitch on the top as shown very clearly at 16, Fig. 3.

Secured to the bed 1 by suitable screws is a bracket 17, which has two uprights 19 and 20 which support the top and bottom trimmer shafts 21 and 22. Secured to the trimmer shaft 21 is a quadrant gear 23 in 30 mesh with a similar gear 24 secured to the companion shaft 22, and which gear 24 is provided with a dependent arm 25 pivotally connected to the forked end 26 of a connecting link or rod 27 actuated by an eccentric 28, Fig. 3, secured to the main driving shaft 10. By this means the proper cutting action is given to the knives. The shafts 21 and 22 have secured thereon the knife levers 29 and 30, which carry the

knives 31 and 32 secured to such levers in any suitable manner. The shafts 21 and 22 are provided with threaded bushings 33, 34 and lock nuts 35 36, between which lock nuts and the quadrant gears 23 and 24 suitable springs 37 are located, each surrounding its shaft. These springs constitute tension means for drawing the knives 31 and 32 against the ledger blades 39 and 40, which latter fit in grooves 41 and 42 of an extension 43 of the upright 19 of the bracket 17.

These ledger blades are held in position by a clamp plate 44 and screw 45. Thus it will be seen that as the main shaft 10 rotates it will, by means of the eccentric 28 secured thereto, effect the rocking of the trimmer

shafts 21 and 22 by means of the quadrant gears, to rock the knife levers 29 and 30 and so cause the knives to coöperate with the ledger blades and effect a shearing cut, which will sever the edges of the top and bottom ply of the collaret strip indicated by 50 and 51 respectively. See Fig. 7.

Any suitable form of right angle binder may be used according to the work to be done. In the present instance this binder head or guide 77 is of the well known right angle construction, consisting of a core and a shell provided with a space between the two for the passage of the strip 78, see Fig. 3. This binder head is carried by a flat extension 76 formed at the end of a slide bar 70, see Fig. 6. To shift the binder head to and from the needle line I provide a yoke 52 attached to the needle lever hub at 53, see Figs. 1 and 2, which yoke is formed to receive a T-shaped sliding block 55, which has connected thereto by a shoulder-screw 56 a lever 57 that is pivotally connected by means of a shoulder-screw 60 with a swinging or rocking plate 58 suitably supported on the bracket 17. Secured to the lever 57 is a connecting link 61 which may be connected at its end, not shown, by a suitable bell crank with a chain and floor treadle whereby the foot of the operator can be used to shift the link 61 in the direction of the arrow, see Fig. 1, so as to force the lever 57 to the dotted line position 51, in which position the lever 57 will have a movement corresponding with the needle lever 7 so as to give a reciprocating movement to the swinging plate 58. When, however, this lever 57 is in the full line position shown in Fig. 1 its connection 56, it will be observed, is in a dead center position relatively to the needle lever stud 59 and consequently it will have no movement and therefore no movement is imparted to the swinging or rocking plate 58, but when this lever 57 has been shifted as hereinbefore described to the dotted line position Fig. 1 it will then move with the needle lever and so shift the swinging plate 58. This plate is provided with a pawl 62 having a spring 63 coöperating therewith to maintain it in engagement with the teeth of a ratchet wheel 64. Secured to this ratchet wheel by screws, the ratchet wheel being suitably supported in juxtaposition to the swinging plate, is a cam plate 67 provided with a groove 68 in which operates a roller stud 69 secured to the end of the slide bar 70 hereinbefore referred to. This slide bar is provided with two elongated slots 71 and 72, see Fig. 6, by means of which and suitable shoulder-screws 74, 75, this bar is secured to a part of the bracket 17 for sliding movement, whereby as this bar is reciprocated back and forth it shifts the binder head 77 hereinbefore referred to toward and from the 125

trimming mechanism in a manner which will be readily understood. Secured to this slide bar 70 is a trip device 79. This trip member coöperates with a lever 81 secured 5 to an upright shaft 82 suitably supported by an upright bracket 84 carried by the bracket 17, this shaft being held in one position by a spring 85, the hooked end 86 of which engages a lever 87 secured to the 10 shaft 82. The end of this lever 87 is provided with a catch 88 in position to coöperate with a catch piece or block 90 secured to the lever 57. As the lever 57 is shifted to the dotted line position shown in 15 Fig. 1 the spring 85 causes the catch 88 of the arm 87 to engage the catch block 90 and so hold the link 57 in such dotted line position, at which time the swinging or 20 rocking plate 58 is caused to oscillate and thereby, through the medium of the pawl 62, to rotate the ratchet wheel 64 one tooth for each revolution of the sewing machine, that is to say each tooth of the ratchet wheel represents a complete cycle of the 25 sewing mechanism equal to a stitch irrespective of its length. In other words, the feed may have a throw of one-eighth of an inch while the space between the ratchet teeth may be three-sixteenths of an inch, 30 or vice versa; so that it will be understood that while the ratchet mechanism is entirely independent of the stitching and feeding mechanism yet it is so timed as to coöperate therewith at the proper time.

35 The operation of the machine is as follows: When the operator starts the machine he simultaneously shifts the link 61 by the means which may be provided for that purpose, and thereby shifts the lever 57 to its 40 dotted line position shown in Fig. 1, so that the catch 88 carried by the arm 87 will engage the catch block 90 of the lever 57 and hold the lever 57 in its operative position. In this position of the lever 57 the movement 45 of the needle lever 7 oscillates or reciprocates the swinging plate 58, which actuates the pawl 62 to shift the ratchet wheel tooth by tooth, and this rotates the cam 67 secured thereto. As the inclined face 93 of 50 the cam groove coöperates with the roller 69 carried by the slide 70 this slide moves to the left or near to the trimming mechanism and so causes a wider margin to be trimmed from the edges of the collaret. 55 This margin gradually increases in width until the roller 69 reaches that portion of the cam groove indicated by 94, whereupon the roller passes into the concentric portion 95 of such cam groove. At this time the 60 binder head or guide is at rest, and during which period a parallel portion is trimmed from the collaret for a distance say of one inch. This is intended to leave a start and finish end and serves as a guide to the operator in starting the shirt neck. When 65

the cam has been shifted around so that the groove at the point 96 reaches the roller 69 the operator immediately starts another shirt neck and the mechanism described continues to operate the binder head, which is gradually drawn away from the trimming mechanism so that the margin trimmed from the collaret strip gradually becomes less, while the collaret stitched to the garment gradually becomes wider until the cam groove 70 has reached the position shown in Fig. 4, at which time the trip device 79 engages the end of the lever 81 to rock such lever 81 and disengage the catch 88 from the block 90 of the lever 57, whereupon the 75 spring 97 connected to this lever 57 returns said lever to its initial or full line position. At this time the binder head shifting mechanism remains at rest, which is after the 80 taper has been produced on the starting 85 end of the shirt neck and while the collaret is being stitched around the remaining portion of the shirt neck until a point is reached which is about an equal distance from the end corresponding to the taper which has 90 been previously made, at which time the link 61 is again shifted by the operator so as to shift the lever 57 to its dotted line position, whereupon on the shifting of the 95 binder head the operation of the binding mechanism is repeated to taper the opposite end of the collaret.

It should be understood that the taper trimmed on the collaret may be varied by regulating the stroke of the feed in any of 100 the usual ways, as it will be obvious that if the stitch is lengthened the collaret strip will have a movement greater than the mechanism for shifting the binder head and so the taper will be longer, while on the 105 other hand, if the stitch be shortened the collaret will move slower, consequently producing a shorter taper. In other words, the length of taper may be varied from one inch to two inches or more. It is furthermore to be understood that the present improvement is not limited to any particular form of cam groove, as it may be desirable to have the binder head shifted three times 110 to each garment so as to produce a low back on the neck, or have the collaret tapered at that portion as well as the front ends thereof. Then again it may be desirable to have the edges scalloped, as for ladies' wear, producing a very ornamental 115 and substantial finish, which would be difficult to produce in any other manner. Various binder guides may be applied to this automatic shifting attachment to handle a flat strip of tape as well as the folded collaret shown in the present instance. Of course it will be understood that when it is desired to stitch a parallel collaret to the garment, or one which has been previously 120 shaped, this can be done by simply disen-

gaging the trimming mechanism, and that the same mechanism may be used as a shiftable edge guide for various forms of work where a uniform product is desired.

5 In practice it is sometimes desirable to in-
turn or fold the edges after the same have
been properly trimmed and before they are
stitched to the garment, and in the present
improvement this may be obtained by form-
10 ing the presser foot and throat plate in the
manner shown in Figs. 9 and 10, by means
of which after the edges of the collaret are
trimmed in the manner hereinbefore de-
scribed they will be folded in by the coöper-
ation of the presser foot and throat plate so

15 that they may pass through the stitching
mechanism in the form shown in Fig. 11.
In such case one needle may be removed.

It is to be understood, as hereinbefore
20 stated, that binders of various sizes or kinds
may be used in connection with the means
for shifting them and that the taper of the
collaret may be varied by regulating the
speed at which the binder head is shifted
25 relatively to the speed of movement of the
material fed to the stitching mechanism.

It will be observed that in the present im-
provement the trimming mechanism is in
30 the form of a duplex trimming means so ar-
ranged that the cutting knives are located
between the binder head and the needles, so
that the paths of travel of the two edges of
such strip or binder will pass between the
35 top and bottom cutters of each set and con-
sequently a portion of the collaret edges
will be trimmed therefrom always to pre-
sent a smooth edge of the collaret strip to
the stitching mechanism.

I claim as my invention:

40 1. In a sewing machine having stitching
and feeding mechanisms, the combination of
means for guiding a strip to the stitching
mechanism, means for trimming such strip,
and means for automatically and continu-
45 ously moving during a predetermined time
the guiding means and trimming means rela-
tively one to the other thereby to trim a
greater portion of the strip at one time than
at another.

50 2. In a sewing machine having stitching
mechanism including a needle actuating le-
ver and feeding mechanism, the combination
of means for guiding a strip to the stitching
mechanism, means for trimming such strip,
55 and means operated by the needle
actuating lever for moving the guiding
means and trimming means relatively one to
the other thereby to trim a greater portion
of the strip at one time than at another.

60 3. In a sewing machine having stitching
and feeding mechanisms, the combination
of means for guiding a strip to the stitching
mechanism, means for trimming such strip,
means for moving the guiding means
65 and trimming means relatively one to the

other thereby to trim a greater portion of
the strip at one time than at another, and
means for automatically throwing such
moving means out of operation at a prede-
termined time.

70 4. In a sewing machine having stitching
and feeding mechanisms, the combination
of means for guiding a strip to the stitching
mechanism, means for trimming such
strip, and automatically operated cam oper-
75 ated means for moving the guiding means
and trimming means relatively one to the
other thereby to trim a greater portion of
the strip at one time than at another.

80 5. In a sewing machine having stitch-
ing and feeding mechanism, the combina-
tion of means for guiding a strip to the
stitching mechanism, means for trimming
such strip, cam-operated means for moving
85 the guiding means and trimming means
relatively one to the other thereby to trim
a greater portion of the strip at one time
than at another, and means for throwing
said cam operated means automatically out
90 of operation at a predetermined time.

95 6. In a sewing machine having stitching
mechanism including a needle actuating
lever and feeding mechanism, the combina-
tion of means for guiding a strip to the
stitching mechanism, means for trimming
100 such strip, and cam operated means con-
nected with said needle actuating lever for
moving the guiding means and trimming
means relatively one to the other thereby
to trim a greater portion of the strip at one
time than at another.

105 7. In a sewing machine having stitching
mechanism including a needle actuating
lever and feeding mechanism, the combina-
tion of means for guiding a strip to the
stitching mechanism, means for trimming
110 such strip, cam operated means connected
with said needle actuating lever for mov-
ing the guiding means and trimming means
relatively one to the other thereby to trim
a greater portion of the strip at one time
than at another, and means for automatically
throwing said cam operated means out
of operation at a predetermined time.

115 8. In a sewing machine having stitching
and feeding mechanisms, the combination of
means for guiding a strip to the stitching
mechanism, means for trimming such strip,
and means connected with one of said mech-
anisms for moving the guiding means and
120 trimming means relatively one to the other
thereby to trim a greater portion of the
strip at one time than at another.

125 9. In a sewing machine having stitching
and feeding mechanisms, the combination
of means for guiding a strip to the stitching
mechanism, means for trimming such strip,
and cam operated means connected
130 with one of said mechanisms for moving
the guiding means and trimming means

relatively one to the other thereby to trim a greater portion of the strip at one time than at another.

10. In a sewing machine having stitching and feeding mechanisms, the combination of means for guiding a strip to the stitching mechanism, means for trimming such strip, cam operated means connected with one of said mechanisms for moving the guiding means and trimming means relatively one to the other thereby to trim a greater portion of the strip at one time than at another, and means for throwing said cam operated means into and out of operation.

11. In a sewing machine having stitching and feeding mechanisms, the combination of means for guiding a strip to the stitching mechanism, means for trimming such strip, and means connected with a part of the stitching mechanism for moving the guiding means and trimming means relatively one to the other thereby to trim a greater portion of the strip at one time than at another.

12. In a sewing machine having stitching mechanism and feeding mechanism, the combination of means for guiding a strip to the stitching mechanism, means for trimming such strip, and cam operated means connected with the stitching mechanism for moving the guiding means and trimming means relatively one to the other thereby to trim a greater portion of the strip at one time than at another.

13. In a sewing machine having stitching mechanism and feeding mechanism, the combination of means for guiding a strip to the stitching mechanism, means for trimming such strip, cam operated means connected with the stitching mechanism for moving the guiding means and trimming means relatively one to the other thereby to trim a greater portion of the strip at one time than at another, means for throwing said cam operated means automatically out of action at a predetermined time, and means for throwing it into action at another time.

14. In a sewing machine having stitching and feeding mechanisms, the combination of means for guiding a strip to the stitching mechanism, means for trimming such strip, and means for so moving continuously during a predetermined time the guiding means and trimming means relatively one to the other as to trim a tapered portion from the strip at one time.

15. In a sewing machine having stitching and feeding mechanisms, the combination of means for guiding a strip to the stitching mechanism, means for trimming such strip, and means for so moving the guiding means and trimming means relatively one to the other thereby to trim tapered portions from the strip at different times to leave the strip

with tapered parts extending in opposite directions.

16. In a sewing machine having stitching and feeding mechanisms, the combination of means for guiding a strip to the stitching mechanism, means for trimming such strip, means for moving the guiding means and trimming means relatively one to the other thereby to trim a tapered portion of material from the strip, said means for moving the guiding means, according to the length of the stitch, regulating the amount of taper.

17. In a sewing machine having stitching and feeding mechanisms, the combination of means for guiding a strip to the stitching mechanism, means for trimming such strip, and means for moving the guiding means and trimming means relatively one to the other thereby to trim a greater portion of the strip at one time than at another, said trimming means being located between the guiding means and the stitching mechanism.

18. In a sewing machine having stitching and feeding mechanisms, the combination of means for guiding a strip to the stitching mechanism, means for trimming such strip, means for moving the guiding means and trimming means relatively one to the other thereby to trim a greater portion of the strip at one time than at another, said trimming mechanism being located between the guiding means and the stitching mechanism, and means under the control of the operator for controlling the action of the said moving means.

19. In a sewing machine having stitching and feeding mechanisms, the combination of means for guiding a strip to the stitching mechanism, means for trimming such strip, means for moving the guiding means and trimming means relatively one to the other thereby to trim a greater portion of the strip at one time than at another, and means for infolding the edge of the strip prior to the stitching thereof.

20. In a sewing machine having stitching and feeding mechanisms, the combination of a strip guiding means for feeding a binding strip in parallel layers to the work, duplex trimming means for trimming both edges of the strip simultaneously, and means for shifting the trimming means and the guiding means one relatively to the other thereby to vary the edges trimmed from the strip.

21. In a sewing machine having stitching and feeding mechanisms, the combination of a strip guiding means for feeding a binding strip in parallel layers to the work, duplex trimming means for trimming both edges of the strip simultaneously, means for so shifting the trimming means and the guiding means one relatively to the other as to trim tapered portions from the edges of the strip at different times with such

portions tapered in opposite directions, and means for infolding both edges of the strip prior to the stitching thereof.

22. In a sewing machine having stitching and feeding mechanisms, the combination of a strip guiding means for feeding a binding strip in parallel layers to the work, duplex trimming means for trimming both edges of the strip simultaneously, means for so shifting the trimming means and the guiding means one relatively to the other as to trim tapered portions from the edges of the strip at different times with such portions tapered in opposite directions, and means for throwing the shifting means into and out of operation.

23. In a sewing machine having stitching and feeding mechanisms, the combination of a strip guiding means for feeding a binding strip in parallel layers to the work, duplex trimming means for trimming both edges of the strip simultaneously, and means connected with one of said mechanisms for shifting the trimming means and the guiding means one relatively to the other thereby to vary the edges trimmed from the strip.

24. In a sewing machine having stitching and feeding mechanisms, the combination of a strip guiding means for feeding a binding strip in parallel layers to the work, duplex trimming means for trimming both edges of the strip simultaneously, and cam operated means for shifting the guiding means relatively to the trimming means thereby to vary the amount trimmed from the edges of the strip.

25. In a sewing machine having stitching and feeding mechanisms, the combination of means for guiding a strip to the stitching mechanism, means for trimming such strip, and automatically operative means for so shifting the guiding means toward and from the trimming means as to trim tapered portions from the strip at different times.

26. In a sewing machine having stitching and feeding mechanisms, the combination of means for guiding a strip to the stitching mechanism, means for trimming such strip, and power driven cam operated means for so shifting the guiding means toward and from the trimming means as to trim a greater portion from the strip at one time than at another.

27. In a sewing machine having stitching and feeding mechanisms, the combination of means for guiding a strip to the stitching mechanism, means for trimming such strip, and automatically operative cam operated means connected with one of said mechanisms for so shifting the guiding means toward and from the trimming means as to vary the portions trimmed from the strip at different times.

28. In a sewing machine having stitching

mechanism including a needle actuating lever and feeding mechanism, the combination of means for guiding a strip to the stitching mechanism, means for trimming such strip, and cam means connected with and operated by the needle actuating lever for moving the guiding means toward and from the trimming means thereby to trim a greater portion from the strip at one time than at another.

29. In a sewing machine having stitching and feeding mechanisms, the combination of means for guiding a strip to the stitching mechanism, means for trimming such strip, means for shifting the guiding means to and from the trimming means thereby to trim a greater portion from the strip at one time than at another, and means for infolding the edge of the strip prior to the stitching thereof.

30. In a sewing machine having stitching and feeding mechanisms, the combination of means for guiding a strip in parallel layers to the stitching mechanism, means for trimming both edges of the strip, and cam operated means connected with one of said mechanisms for shifting the guiding means toward and from the trimming means thereby to trim tapered portions from the strip at different times with such tapered portions extending in opposite directions.

31. In a sewing machine having stitching and feeding mechanisms, the combination of strip guiding means for feeding a binding strip in parallel layers to the stitching mechanism, duplex trimming means for trimming both edges of the strip simultaneously, cam means for shifting the guiding means relatively to the trimming means thereby to vary the amount trimmed from the edges of the strip, and ratchet mechanism for operating said cam means.

32. In a sewing machine having stitching and feeding mechanisms, the combination of strip guiding means for feeding a binding strip in parallel layers to the stitching mechanism, duplex trimming means for trimming both edges of the strip simultaneously, cam means for shifting the guiding means relatively to the trimming means thereby to vary the amount trimmed from the edges of the strip, ratchet mechanism for operating said cam means, and means connected with the stitching mechanism for operating said ratchet mechanism.

33. In a sewing machine having stitching and feeding mechanisms, the combination of strip guiding means for feeding a binding strip in parallel layers to the stitching mechanism, duplex trimming means for trimming both edges of the strip simultaneously, cam means for shifting the guiding means relatively to the trimming means thereby to vary the amount trimmed from the edges of the strip, ratchet mechanism for operating

mechanism and feeding mechanism, the combination of a strip guiding means for feeding a binding strip in parallel layers to the stitching mechanism, duplex trimming means for trimming both edges of the strip simultaneously and comprising a pair of fixed blades and a pair of oscillating blades, shafts for supporting the latter, means for rocking said shafts, a sliding bar carrying said strip guiding means, and cam operated means for reciprocating said bar toward and from the trimming means.

43. In a sewing machine having stitching mechanism including a needle actuating lever and feeding mechanism, the combination of strip guiding means for feeding a binding strip in parallel layers to the stitching mechanism, duplex trimming means located between the strip guiding means and the stitching mechanism for trimming both edges of the strip simultaneously and comprising a pair of fixed blades and a pair of shiftable blades, a pair of shafts for carrying said shiftable blades, means for rocking said shafts, a sliding bar carrying said strip guiding means, a cam for reciprocating said bar toward and from the trimming means thereby to trim tapered portions from the strip, ratchet mechanism for rotating said cam, a lever connected to said ratchet mechanism and having a sliding pivotal connection with the needle actuating lever for operating said ratchet mechanism and thereby the cam, means for shifting said sliding pivotally connected lever into position relatively to the needle actuating lever thereby to throw the cam into operation, means for holding said lever in such position, and means operated by the sliding bar for automatically releasing said holding means thereby to stop the movement of the cam.

44. In a sewing machine having stitching mechanism including a needle actuating lever and feeding mechanism, the combination of strip guiding means for feeding a binding strip in parallel layers to the stitching mechanism, duplex trimming means located between the strip guiding means and the stitching mechanism for trimming both edges of the strip simultaneously and comprising a pair of fixed blades and a pair of shiftable blades, a pair of shafts for carrying said shiftable blades, means for rocking said shafts, a sliding bar carrying said strip guiding means, a cam for reciprocating said bar toward and from the trimming means thereby to trim tapered portions from the strip, ratchet mechanism for rotating said cam, a lever connected to said ratchet mechanism and having a sliding pivotal connection with the needle actuating lever for operating said ratchet mechanism and thereby the cam, means for shifting said sliding pivotally connected lever into position relatively to the needle actuating lever thereby to throw the cam into operation, means for holding said lever in such position, and means operated by the sliding bar for automatically releasing said holding means thereby to stop the movement of the cam.

45. In a sewing machine having stitching mechanism including a needle actuating lever and feeding mechanism, the combination of strip guiding means for feeding a binding strip in parallel layers to the stitching mechanism, duplex trimming means located between the strip guiding means and the stitching mechanism for trimming both edges of the strip simultaneously and comprising a pair of fixed blades and a pair of shiftable blades, a pair of shafts for carrying said shiftable blades, means for rocking said shafts, a sliding bar carrying said strip guiding means, a cam for reciprocating said bar toward and from the trimming means thereby to trim tapered portions from the strip, ratchet mechanism for rotating said cam, a lever connected to said ratchet mechanism and having a sliding pivotal connection with the needle actuating lever for operating said ratchet mechanism and thereby the cam, means for shifting said sliding pivotally connected lever into position relatively to the needle actuating lever thereby to throw the cam into operation, means for holding said lever in such position, and means operated by the sliding bar for automatically releasing said holding means thereby to stop the movement of the cam.

46. In a sewing machine having stitching mechanism, feeding mechanism, a throat plate and a presser foot, the combination of means for guiding a strip to the stitching mechanism, means for trimming such strip, means for moving the guiding means and trimming means relatively one to the other thereby to trim a greater portion from the strip at one time than at another, and means carried by the presser foot and throat plate for infolding both edges of the strip after the trimming thereof.

47. In a sewing machine having stitching mechanism, feeding mechanism, a throat plate and a presser foot, the combination of means for guiding a strip in parallel layers to the stitching mechanism, means for trimming such strip, means for moving the guiding means and trimming means relatively one to the other thereby to trim a greater portion from the strip at one time than at another, and means carried by the presser foot and throat plate for infolding both of such trimmed edges.

48. In a sewing machine having stitching and feeding mechanisms the combination of

throw the cam into operation, means for holding said lever in such position, means operated by the sliding bar for automatically releasing said holding means thereby to stop the movement of the cam, and means for infolding both edges of the strip prior to the stitching thereof.

45. In a sewing machine having stitching mechanism including a needle actuating lever, feeding mechanism, a throat plate and a presser foot, the combination of strip guiding means for feeding a binding strip in parallel layers to the stitching mechanism, duplex trimming means located between the strip guiding means and the stitching mechanism for trimming both edges of the strip simultaneously and comprising a pair of fixed blades and a pair of shiftable blades, a pair of shafts for carrying said shiftable blades, means for rocking said shafts, a sliding bar carrying said strip guiding means, a cam for reciprocating said bar toward and from the trimming means thereby to trim tapered portions from the strip, ratchet mechanism for rotating said cam, a lever connected to said ratchet mechanism and having a sliding pivotal connection with the needle actuating lever for operating said ratchet mechanism and thereby the cam, means for shifting said sliding pivotally connected lever into position relatively to the needle actuating lever thereby to throw the cam into operation, means for holding said lever in such position, means operated by the sliding bar for automatically releasing said holding means thereby to stop the movement of the cam, and means carried by the presser foot and throat plate for infolding both edges of the strip after the trimming thereof.

46. In a sewing machine having stitching mechanism, feeding mechanism, a throat plate and a presser foot, the combination of means for guiding a strip to the stitching mechanism, means for trimming such strip, means for moving the guiding means and trimming means relatively one to the other thereby to trim a greater portion from the strip at one time than at another, and means carried by the presser foot and throat plate for infolding the so trimmed edge.

47. In a sewing machine having stitching mechanism, feeding mechanism, a throat plate and a presser foot, the combination of means for guiding a strip in parallel layers to the stitching mechanism, means for trimming such strip, means for moving the guiding means and trimming means relatively one to the other thereby to trim a greater portion from the strip at one time than at another, and means carried by the presser foot and throat plate for infolding both of such trimmed edges.

48. In a sewing machine having stitching and feeding mechanisms the combination of

- means for guiding a strip to the stitching mechanism, means for automatically moving the guiding means relatively to the path of stitching, and means for folding the edge of 5 the strip prior to the stitching thereof.
49. In a sewing machine having stitching and feeding mechanisms the combination of shiftable means for guiding the strip to the stitching mechanism, means connected with 10 the stitching mechanism for automatically shifting the strip guiding means to and fro relatively to the line of stitching, and means for infolding the edges of the strip prior to the stitching thereof.
- 15 50. In a sewing machine having stitching and feeding mechanisms the combination of shiftable means for guiding the strip to the stitching mechanism, means for automatically shifting the strip guiding means to 20 and fro relatively to the line of stitching, means for infolding the edges of the strip prior to the stitching thereof, and means for automatically throwing said strip guiding means out of action at a predetermined time.

51. In a sewing machine having stitching 25 and feeding mechanisms the combination of a strip guiding means for feeding a binding strip in parallel layers to the work, means for automatically shifting the guiding means relatively to the line of stitching, and means 30 for infolding both edges of the strip prior to the stitching thereof.

52. In a sewing machine having stitching and feeding mechanisms the combination of strip guiding means for feeding a binding 35 strip to the work, means for automatically shifting said guiding means relatively to the line of stitching, and means for automatically throwing said strip guiding means out of action at a predetermined time. 40

Signed at Nyack, in the county of Rockland and State of New York, this 24th day of July, 1912.
